UNITED STATES PATENT OFFICE.

WILLIAM E. MILLER, OF ALLEGAN, MICHIGAN.

MACHINE FOR SEALING WRAPPERS UPON LOAVES OF BREAD.

1,142,976.

Specification of Letters Patent. Patented June 15, 1915.

Application filed April 21, 1913. Serial No. 762,705.

To all whom it may concern:

Be it known that I, WILLIAM E. MILLER, a citizen of the United States, residing at Allegan, in the county of Allegan and State 5 of Michigan, have invented certain new and useful Improvements in Machines for Sealing Wrappers upon Loaves of Bread, of which the following is a specification.

My invention relates to improvements in 10 implements for sealing paper that is wrapped around loaves of broad or other oblong packages, and its objects are: first, to provide a means whereby the loaves, first wrapped with paper, may be passed through 15 between properly prepared and heated plates and the wax heated and cooled so as to secure the paper around the loaf without the necessity of wrapping it with twine; and, second, to provide a means whereby the 20 wax may be readily cooled in extremely hot weather.

I attain these objects by the mechanism illustrated in the accompanying drawing, in which—
25 Figure 1 is a top plan of the machine complete. Fig. 2 is an end elevation of the same with the outline of a loaf in place; and, Fig. 3 is a bottom plan of the machine.

Similar letters refer to similar parts 30 throughout the several views.

In the construction of this machine I secure longitudinal cleats A, and C to cross girts B and B'. The cross girts B B have legs made integral therewith, as indicated 35 in Fig. 2, and the cross cleats B', B', have standards G G integral therewith and extending upward at right angles therefrom to act as supports for the permanent plate E, which is secured to the longitudinal cleat C. The cleat C' is secured to the cross slides M, which in turn are slidably secured 40 to the cross cleats B' by means of the brackets N N so that they may be readily adjusted to any desired width or length of 45 loaf that is to be sealed. The sliding cleats M, also have upwardly extending standards, G' G' to which the plate E' is secured, the plates E and E' being made to stand edge-wise and parallel with the corresponding

standards and supported thereon as follows: 50 The plates E and E' have bolts g' g' secured to them and extending outward at right angles therefrom, and passing through the standards and properly secured to slide freely, and a properly arranged spring, as g, 55 is placed on each bolt between the standard and the plate so that the plates are held forcibly away from the standards, and yet may be readily adjusted to the form of the loaf, and to slight variations in the lengths 60 of the loaves. Thus, if a loaf is perpendicular at the ends the plates will stand vertical edgewise, as indicated by their solid lines in Fig. 2, but if the loaf is a little flaring at the ends, as indicated by the dotted outlines of the loaf K in Fig. 2 the plates will be adjusted to the flare, as indicated by the dotted lines in said figure.

The sliding cleats M M are provided with a series of small teeth or serrations i' with 70 which the pawls I' are designed to engage for the purpose of holding these slides or cleats from being forced outward when a loaf is being passed between the plates E. These pawls may be attached to the machine 75 in any available manner, but I prefer that they be made integral with a long spring wire I, which may be secured to the frame by means of interlocking with small standards or bolts n n n', as indicated in Fig. 3, 80 and so arranged that the pawls will stand normally in engagement with the serrations i', and to disengage the pawls from these teeth I pivot a lever F to a center cross cleat B'', as at f, and connect the respective 85 pawls therewith by means of connecting rods J J that are secured at one end to the lever as at f' f' and at the other ends to the loops i i in the pawl spring I I', so that when the lever is thrown around to the position of its 90 dotted lines in Fig. 3 the pawls will be drawn out of engagement with the teeth i' and the cleats M M may be slid outward to provide for adjusting the distance between the plates E and E' to accommodate loaves 95 of considerable variation in length, as indicated by the dotted outlines of the plate E' and its supporting cleats in Figs. 2 and 3.

For the purpose of producing heat to melt the wax on the paper with which the loaves are wrapped, I place a heating chamber, D, upon one end of each of the side 5 plates and, preferably, place an electric bulb II' therein by means of which heat is electrically produced through the medium of the armatures H H and the connecting wires h and h' properly connected with a 10 source of electricity. At the lower side of Fig. 3 I have shown the chamber in section to more fully disclose the position and form preferred for the bulb, and, also, to disclose a non-conducting lining in the 15 chamber, as indicated at d, to insure the desired distribution of the heat.

In cool weather the wax will cool before it has passed from between the plates E and E', but in extremely warm weather it is 20 necessary to employ some artificial means for cooling it, and for this purpose I place a water tank O, O', on the plates back of the heating chambers D D and make provisions for having a constant flow of cool 25 water as follows: Water is forced into the tank O through the pipe o, thence out at l through the hose or flexible pipe L to l' where it passes into the tank O', and is carried out of the tank O' by the pipe o', it being understood that the proper water 30 connections are made with the pipes o and o', though the same are not here shown.

The plates E E' are, preferably, curved outward at one end, as at E'', so the loaves 35 may be readily passed between them when feeding to the machine.

It will be readily understood that the direction of the circulation of water through the tanks O and O' is optional with the operator, as the supply pipe may be connected 40 with the pipe o' and the drain connected with the pipe o, and in some instances this direction of flow will be found preferable as the pipe o being shown as at the top of 45 the tank, both tanks must be full of water at all times, while with the supply and drain pipes filled from the other way there is danger that the tank O' might not remain full, especially if the pressure is not great in the 50 supply pipe.

What I claim as new and desire to secure by Letters Patent of the United States, is:

1. In combination with a supporting frame in a machine for sealing paper wrappers on oblong loaves, permanent standards 55 extending upward from one side of the frame, laterally adjustable standards projecting upward from the other side of said frame, sealing plates secured parallel with 60 said standards at one end of the machine, and cooling plates at the other end of the machine, means for allowing of slight temporary lateral automatic adjustment to said

plates independent of the standards, and means for heating one end of each of said 65 sealing plates sufficiently to melt wax as it comes in contact with them.

2. In combination with the supporting frame of a machine for sealing wrappers on oblong loaves, permanent standards projecting upward from one side of the frame, laterally adjustable standards projecting upward from the other side of the frame, sealing plates placed parallel with the standards and secured thereto in such a manner 70 as to be laterally adjustable automatically to the form of the loaf, independent of the standards, heating appliances connected with one end of each sealing plate, and a cooling appliance connected with the other 80 end of the machine.

3. In combination with the supporting frame of a machine for sealing wrappers upon oblong loaves, permanent standards extending upward from one side of the 85 frame, sliding cleats secured under the frame so that the width of the machine may be varied, standards extending upward from the outer ends of said cleats, a vertically disposed sealing plate secured to the standards at each side of the machine, teeth formed on the inner edges of the sliding cleats, spring actuated pawls arranged to engage said teeth to hold the sliding cleats temporarily in the desired positions, a heating appliance connected with each of the sealing plates, and a cooling appliance attached to the machine back of each sealing plate and arranged for a continuous circulation of cold water therethrough.

4. In combination with the supporting frame of a machine for sealing wrappers on oblong loaves, permanent standards extending upward from one side of the machine, laterally adjustable standards extending upward from the other side of the machine, sealing plates adjustably connected with said standards and having one end of each curved outward, slides integral and at right angles with the adjustable standards and arranged to slide under the surface of the frame for lateral adjustment, means for temporarily securing the slides to the frame and for temporarily releasing them when desired, heaters connected with the plates at 105 one end of the machine, and cooling appliances connected at the other end of the machine.

5. In combination with the supporting frame of a machine for sealing wrappers on oblong loaves, permanent standards secured to, and extending upward from one side of the machine, standards at the other side of the machine secured to slides and arranged for laterally adjusting the width of the machine, a sealing plate at each side of the ma- 115 120 125

chine, bolts passed through the standards and secured to the plates to hold them in vertical position, springs upon said bolts between the standards and the sealing plates 5 for slight lateral adjustment of said plates at the upper edge, the lower edge, either end or bodily as required, and means for heating and cooling the wax as the loaves are passed through the machine, substantially

as shown and described, and for the purpose set forth.

Signed at Grand Rapids Michigan April 15 1913.

WILLIAM E. MILLER.
